UNITED STATES PATENT OFFICE.

EDWARD J. CHILDRESS, OF ALTAVISTA, VIRGINIA.

CURTAIN-BRACKET.

1,034,977.

Specification of Letters Patent.

Patented Aug. 6, 1912.

Application filed October 10, 1911. Serial No. 653,831.

To all whom it may concern:

Be it known that I, EDWARD J. CHILDRESS, a citizen of the United States, residing at Altavista, in the county of Campbell and State of Virginia, have invented new and useful Improvements in Curtain-Brackets, of which the following is a specification.

The present invention relates to improvements in curtain brackets.

10 In carrying out my invention it is my purpose to provide a bracket which may be easily and quickly secured to or removed from a window casing without the application of nails or other securing elements, and 15 which while adjustable both vertically and longitudinally upon the casing may be readily removed therefrom when desired.

I also aim to provide a bracket of this character constructed of a single piece of 20 spring material having the portion forming the horn thereof provided with spaced walls, and means for compressing the walls, one toward the other to draw the opposite ends of the fixture, which are provided with off- 25 set bracket engaging elements, together so that the said bracket engaging elements will tightly contact with both the upper and lower edges of the casing.

It is also my purpose to provide a bracket 30 of this character wherein the lower off-set engaging portion may be dispensed with when the fixture is to be attached to the extreme ends of the casing and especially when 35 a miter joint instead of the ordinary block is employed, in which instance the bracket is provided with an opening adapted for the 40 reception of a single tack and the upper portion thereof is tightly secured to the top of the casing through the medium of a compressible horn.

With the above recited objects in view, the improvement resides in the construction, combination, and arrangement of parts set forth in and falling within the scope of the 45 appended claims.

In the drawings, Figure 1 is a perspective view of the improved bracket, showing the same applied to a window frame. Fig. 2 is a central vertical longitudinal sectional view of the bracket. Fig. 3 is a view of a modified form of the bracket.

Referring now to the drawings in detail the numeral 1 designates an ordinary window casing, and 2 my improved bracket 50 which is adapted to be attached to the casing. The bracket is formed from a single

piece of resilient material such as brass or the like, and comprises an elongated member having both its upper and its lower edges bent at a substantially right angle of the 60 bracket proper as indicated by the numerals 3 and 4. Both of these offsets or frame engaging elements preferably have their inner edges bent to provide teeth which engage the upper and lower edges of the casing when 65 the bracket is in position upon the casing, so as to prevent an accidental longitudinal movement of the bracket.

The front or body of the bracket, designated by the numeral 5 has one of its ends 70 offset as at 6 to provide a shade engaging member, and the said body is bent upon itself to provide the substantially semi-cylindrical horn 7. It will be noted by reference to the figures of the drawings that 75 the wall 8 of the upper portion of the horn is spaced a suitable distance away from the wall of the lower portion 9 of the horn, and both of these walls are provided with registering openings 10 and 11. The opening 10 80 is reamed for the reception of a head 12 of a bolt 13. This bolt is non-threaded and has its lower portion which extends through the opening 11 pivotally connected as at 14 between the bifurcated head 15 of a cam 85 member 16. This cam member is provided with a depending arm 17 and it will be readily noted that by swinging the arm of the cam member in one direction will cause the said cam to force the bolt downwardly 90 and bring the cam into contact with the under face of the wall 9 so as to compress the walls 8 and 9 together and as a consequence bring their offset or contacting ends tightly into engagement with both the upper 95 and lower edges of the window casing.

In Fig. 3 I have illustrated a bracket which may be employed at the extreme ends of a window casing. In this instance the lower offset engaging portion is dispensed 100 with and the lower face or body of the bracket is provided with a single opening α , the same being adapted to receive some retaining element such as a headed tack or the like, the remainder of the structure being 105 similar to that heretofore described.

From the above description taken in connection with the accompanying drawings the simplicity of the device as well as the advantages thereof will, it is thought commend themselves to those skilled in the art to which such inventions appertain. It is

also to be stated that I am aware of the fact that numerous devices have been employed whereby curtain brackets are attached to window frames without the employment of 5, nails, screws and the like, and I do not claim broadly such a structure but

What I do claim is:—

1. A window bracket constructed of resilient material and having offset engaging 10 members, said bracket being provided with a horn having spaced walls, and means connected with the horn for compressing the walls thereof to bring the engaging portions of the bracket toward each other.
- 15 2. A window shade bracket constructed of a single piece of resilient material, and having its opposite ends offset and provided

with teeth, the bracket being bent upon itself to provide a horn, the upper and lower walls provided by the said horn being spaced 20 away from each other a bolt carried by the upper wall and extending through the lower wall, and a cam member provided with a handle connected with the bolt and adapted to be swung into engagement with the lower 25 wall to compress the walls of the horn to bring the offset ends of the bracket toward each other.

In testimony whereof I affix my signature in presence of two witnesses.

EDWARD J. CHILDRESS.
